FORCE FEED MECHANICAL LUBRICATOR

Francis L. Hamill, Litchfield, Conn., assignor to
The Torrington Manufacturing Company, Tor-
rington, Conn., a corporation of Connecticut

Application October 10, 1931. Serial No. 568,077

5 Claims. (Cl. 184—27)

This invention relates to new and useful im-
provements in force feed mechanical lubricator.

An object of the invention is to provide a
lubricator of the kind indicated and which in-
cludes a pump, means for adjusting the stroke of
the pump, means providing for the hand
operation of the pump, and a sight feed if desired,
all assembled or mounted as a unit and adapted
as a unit to be easily and quickly mounted on
10 or removed from a reservoir box or the like.

Another object is to provide a force feed me-
chanical lubricator wherein all the necessary
parts with the exception of a shaft and operating
cam or eccentric are assembled or mounted as
15 a unit whereby the lubricator may be easily and
quickly applied to or removed from a reservoir
box.

A further object is to provide a force feed me-
chanical lubricator including novel means pro-
20 viding for adjustment of the stroke of the pump
and including novel hand operation means for
the pump, which hand operation means operates
through the means for adjusting the stroke of
the pump.

25 Other objects and advantages will become
apparent from a consideration of the following
detailed description taken in connection with the
accompanying drawings wherein a satisfactory
embodiment of the invention is shown. It is, of
30 course, to be understood that the invention is not
limited to the details disclosed but includes all
such variations and modifications as fall within
the spirit of the invention and the scope of the
appended claims to which reference should be
35 had for a definition of the invention.

In the drawings:

Fig. 1 is a view partly in front elevation and
partly in section and showing a plurality of the
improved lubricators mounted on a reservoir box
40 or the like; and

Fig. 2 is a vertical sectional view through one
of the improved lubricators.

Referring in detail to the drawings, at 5 is
shown a reservoir box or the like adapted to con-
45 tain a lubricant, and in a side wall 6 of this box
there is provided a stuffing-box 7 through which
extends a shaft 8 driven by any suitable means
9 from any suitable source of power, not shown,
such for example the prime mover to be lubri-
50 cated. The upper side of the box 5 is open and
surrounding the opening is a ledge 10 on which
may be disposed a cover 11, in the front wall 12
of the box 5 are upper and lower windows or
sights 13 and 14 whereby the height of the lubri-
55 cant in the reservoir may be readily ascertained.
If desired, a baffle 15 may be provided within the
reservoir in spaced relation to the sights 13 and
14 and painted white to provide a light back
ground to facilitate gauging the oil level in the
60 reservoir.

In Fig. 1 four of the improved force feed lubri-
cators are shown as mounted on the reservoir box
5 although it will be understood that a greater
or lesser number of lubricators may be used on
a single reservoir box. The lubricators are each
65 independent of the other and are each of the
same or substantially the same construction and
a detailed description of one will it is believed
suffice for all. All of the parts of each lubricator
are mounted on a supporting member or bar 16 70
whereby the lubricators may each be removed
and replaced independent of one another. From
this it will be understood that each mounting
member 16 has a complete lubricator assem-
blie thereon and that the lubricators are not depend- 75
ent on one another in their operation.

Depending from or disposed at the under or
lower side of the supporting member 16 is a
barrel or casing or tube 17 the upper end por-
tion of which projects through the member 16 80
and is externally screw threaded as at 18. A nut
19 disposed on the threads 18 is turned down to
engage the upper surface of the member 16
whereby to clamp the casing 17 to the member
16. A suction tube 20 depends from the lower 85
end of the barrel 17 and of course, communicates
with the interior of the barrel.

Extending laterally from and communicating
with the interior of the barrel 17 is a pump 21
comprising a cylinder 22, screw threaded into a 90
wall of the barrel or casing 17, and a piston or
plunger 23 operating in the pump cylinder 22.
To the outer end of the plunger or piston 23 is
threaded a head or nut 24, and surrounding the
cylinder 22 and bearing at one end against this 95
nut or head 24 is a coil spring 25. This coil spring
operates the plunger or piston on its suction or
return stroke.

Within the barrel or casing 17 and above and
below the point of communication between said 100
barrel and the pump cylinder 22 are suitable ball
check valves 26 and 27 whereby on the stroke of
the plunger 23 under the influence of the spring
25 lubricant is drawn into the barrel 17 through
the tube 20 and ball checks 27 and on the return 105
or power stroke the said lubricant is forced up-
wardly in the barrel to the upper side of the ball
checks 26.

If desired there may be arranged at the upper
side of the mounting member 16 and communi-
cating with the barrel or casing 17 a sight feed
28 including a glass 29 and a wire 30 along which
the lubricant may travel. The sight feed may
contain water, glycerin or salt water, and the
lubricant passing through the sight feed enters 115
a conduit 31 which may conduct the lubricant to
its point of application or use. This sight feed
is not necessarily applied as shown but may be
located remote from the lubricator if preferred.
For example it may be installed in the delivery 120

line immediately at the point of application of lubricant to bearing or cylinder.

The pump plunger or piston 23 is given its delivery or power stroke by means of a cam or eccentric 32 on the shaft 8 and against which the nut or head 24 may bear. However, the stroke of the pump plunger is adjustable or variable to vary the rate of feed of the lubricant as will later appear and it may be that on its return or suction stroke it will not remain in contact with the low portion of a cam or eccentric. As the eccentric is rotated its high portion will engage the nut or head 24 and force the plunger 23 inwardly of the cylinder against the action of the spring 25, operating the plunger on its delivery stroke, and as the high point of the cam or eccentric recedes the spring 25 starts the return or suction stroke of the plunger.

Means are provided for varying the stroke of the plunger 23 and this means includes a bracket or bell crank 33 having an arm 34 and a bifurcated or pair of spaced downwardly extending arms 35. The arms 35 engage the head or nut 24 and since these arms are somewhat spaced the cam or eccentric 32 operates between them. Bracket or bell crank 33 is pivotally mounted as on a pin 36 supported by an eye 37 depending from the mounting member 16 and secured to the said mounting member as by a nut 38 threaded to the stem of the eye.

At its outer or free end the arm 34 of the bracket 33 may carry a lug or bumper 39 adapted to be engaged as and for a purpose to be described. Threaded through the member 16 in line with the outer portion of the said arm 34 is an elongated cylindrical member 40 adapted to be adjusted through the member 16 whereby to adjust the position of the bracket 33 on its pivot to thus limit the stroke of the pump plunger and determine the length of its stroke. A nut 41 is threaded on the member 40 so as to lock the same in adjusted position and to adjust the member downwardly so as to rock the bracket in a counter clock-wise direction or in a direction to move its arms 35 towards the pump cylinder it is but necessary to loosen the nut 42 and then turn the member 40.

As the member 40 is threaded through the supporting member 16 the arm 34 of the bracket will of course be rocked downwardly and the arms 35 will be moved in a direction to force the plunger inwardly of the cylinder 22 against the action of the spring 25 and thus shorten its stroke by shortening its reverse movement under action of spring 25. The member 40 is then locked in adjusted position by means of the nut 41. Within the cylindrical member 40 is a plunger 42 which carries a stem 43 extending outwardly of the member 40 and at its upper end carrying a push button 44. Obviously, by depressing the push button 44 the plunger 42 will be projected from the elongated member 40 to rock the bracket 35 about its pivot and cause it to operate the plunger 23 in the manner in which the plunger would be operated by the cam 32 were the cam turned.

On the hand plunger being released the spring 25 would of course operate to return the parts to normal position. However, to keep the lug 39 on the arm 34 of the bracket in constant engagement with the plunger 42 irrespective of the location of the pump plunger or the spring 25, a spring 45 is disposed on the pivot 36 and this spring has an arm 46 engaging the arm 34 of the bracket whereby the spring tends to rotate the

arm and as a matter of fact the whole bracket in clock-wise direction thereby maintaining the lug 39 in constant engagement with the plunger. This prevents the plunger 42 and hand button 44 from moving up and down with the reciprocating movements of the plunger during normal operation.

Since as the elongated cylindrical member 40 is adjusted through the supporting member 16 the hand operation plunger 42 will necessarily move with the member 40 it will be obvious that the extent to which the member 40 is adjusted through the support will determine the extent of the clock-wise movement of the bracket 33 and thus the extent of the return or suction of the pump plunger 23. It will further be apparent that the means for adjusting the stroke of the pump plunger is mounted on the supporting member 16 as are the other parts of the improved force feed lubricator. Additionally, it is to be noted that the hand operation plunger 42 operates the pump plunger or piston through the bracket 33 whereby it is not necessary to provide additional mechanism for the hand operation.

It is believed that the construction and operation of the force feed mechanical lubricator of the present invention will now be fully understood. However, it is desired to point out that the entire lubricator is mounted and secured to the reservoir box 5 by means of two screws 47 one of which is passed through each end of the supporting member 16 and into the box 5. When a plurality of lubricators are used in connection with a single reservoir as shown in Fig. 1 it will be apparent that any lubricator may be removed from the reservoir without in any way interfering with the operating of the other lubricators on the reservoir.

When one of the lubricators is removed from a reservoir the screws 47 are simply loosened and the lubricator lifted off without stopping or in any way disturbing the other lubricators. After repairs the removed lubricator may be remounted on the reservoir without disturbing the other lubricators which may be in operation. All parts are removed with the exception of the eccentric or cam and the shaft and all parts are removed and applied as a unit. The unit could be placed on a machine tool, the manufacture of the machine tool locating the cam or eccentric on the machine. In other words the entire unit can be placed wherever desirable it being merely necessary to provide an oil reservoir and an operating means for the pump. With this arrangement the entire lubricator can be assembled and adjusted at any location desired and then placed in operation by merely mounting it on the reservoir. Having thus set forth the nature of my invention, what I claim is:

1. In a force feed mechanical lubricator, a removable unit comprising a mounting member, an outlet for lubricant on said member, a pump on said member including a plunger and adapted to pump lubricant through said outlet, means mounted on said member and movable therewith as a unit and adjustable while the unit is removed to shift the plunger to adjust the stroke of the pump, hand operation means for the pump, said hand operation means mounted on said member to move therewith as a unit, an operative means for transmitting movement from the hand operation means to the pump, means mounting said operative means on said member, and means to removably mount the said mounting member on a reservoir box.

2. In a force feed lubricator, a removable unit assembly comprising a mounting member, means for conducting lubricant to a place of use and connected with said member, a pump on said member and adapted to pump lubricant through said conductor, said pump including a cylinder and a plunger and a spring means for moving said plunger in one direction relative to the cylinder, means mounted on the member and having a pair of arms one of which engages the outer end of the plunger, means adjustably mounted on the member and engaging the other arm of said means and adapted to be adjusted to adjust said means and thereby the stroke of the pump, a hand operation means also mounted on said member and engaging one of the arms of said means, and means to removably secure said member to a reservoir to mount said unit assembly thereon.
3. In a force feed lubricator, a removable unit assembly comprising a pump including a piston and a cylinder and a spring means for operating the piston on its return stroke, means for adjusting the stroke of the piston, said means including a bracket having two arms one of which engages the outer end of the piston, means pivotally mounting said bracket, an externally threaded tubular member engaging the other arm of the bracket, said member threadedly adjustable to rock said bracket in one direction on its pivot to control the extent of the return movement of the piston under the influence of the spring means, a hand operation means for imparting the delivery stroke to the piston, and said hand operation means including a plunger operating through said tubular member and engaging the said other arm of the bracket, a mounting member adapted to be removably mounted on the top of a reservoir, and all of said elements and means being
4. In a force feed lubricator, a pump including a piston and a cylinder and a spring means for operating the piston on its return stroke, means for adjusting the stroke of the piston, said means including a bracket having two arms one of which engages the outer end of the piston, means pivotally mounting said bracket, an externally threaded tubular member engaging the other arm of the bracket, said member threadedly adjustable to rock said bracket in one direction on its pivot to control the extent of the return movement of the piston under the influence of the spring means, a hand operation means for imparting the delivery stroke to the piston, and said hand operation means including a plunger operating through said tubular member and engaging the said other arm of the bracket, and a spring means engaging the bracket and operating to maintain the bracket positioned with its said other arm in engagement with the hand plunger irrespective of the position of the piston.
5. In a force feed lubricator, a pump including a piston and a cylinder and a spring for operating the piston on its return stroke, means for adjusting the stroke of the piston, said means including a bracket having a pair of arms one of which is bifurcated and engages the outer end of the piston, a cam adapted to engage the outer end of the piston between the parts of the bifurcated arm to impart the delivery stroke to the piston, means pivotally mounting said bracket, means engaging the other arm of the bracket, and said last means adjustable to rock said bracket on its pivot to adjust the position thereof and thereby adjust the return stroke of the piston under the influence of the spring.
